CLAIM

The ornamental design for a cycle locker, as shown and described.

DESCRIPTION

FIG. 1 is a perspective view of a cycle locker showing my new design with rounded front and rear faces;

FIG. 2 is a right side view of FIG. 1, and the left side view being a mirror image thereof;

FIG. 3 is a front side view of FIG. 1;

FIG. 4 is a rear side view of FIG. 1;

FIG. 5 is a top plan view of FIG. 1;

FIG. 6 is a perspective view of an alternative embodiment of my cycle locker design with flat front and rear faces;

FIG. 7 is a right side view of FIG. 6, and the left side view being a mirror image thereof;

FIG. 8 is a front side view of FIG. 6;

FIG. 9 is a rear side view of FIG. 6; and,

FIG. 10 is a top plan view of FIG. 6.
